Application November 30, 1948, Serial No. 149,887
In Great Britain August 23, 1948

Term of patent 14 years

(Cl. D34—13)

To all whom it may concern:

Be it known that we, Arthur Louis Hirst, a resident of Caerleon, Halton Green, Halton, near Lancaster, and Vernon Mansell Bullock, a resident of Sunnycroft, Nether Kellet, near Carnforth, both in the county of Lancaster and Kingdom of England, both British subjects, have invented a new, original, and ornamental Design for a Playing Card or Similar Article, of which the following is a specification, reference being had to the accompanying drawing, forming part thereof.

Fig. 1 is a plan view of a playing card showing our new design; and

Fig. 2 is an edge view thereof.

The opposite side of the card is conventional.

The dotted line showing in Figure 1 of the drawing is for illustrative purposes only.

We claim:

The ornamental design for a playing card or similar article, as shown and described.

ARTHUR LOUIS HIRST.
VERNON MANSELL BULLOCK.
